UNITED STATES PATENT OFFICE.

JOSIAH LETCHWORTH, OF BUFFALO, NEW YORK.

HAME.

SPECIFICATION forming part of Letters Patent No. 415,722, dated November 26, 1889.

Application filed June 15, 1889, Serial No. 314,427. (No model.)

To all whom it may concern:

Be it known that I, JOSIAH LETCHWORTH, a citizen of the United States, residing at Buffalo, in the county of Erie and State of New York, have invented new and useful Improvements in Line-Rings for Hames, of which the following is a specification.

This invention relates to the line-rings which are attached to hames and through which the reins pass. Heretofore the line-ring has been attached to the hame by one or more staples or rivets embracing journals on the ring, so as to permit the ring to swivel backwardly and forwardly on the hame. In the ordinary construction of these rings the journals are formed on the inner bar of the ring and the eyes of the staples embracing these journals project inwardly beyond the inner surface of the ring. This is objectionable, because the projections so formed on the inner bar of the ring chafe and wear the reins.

The object of my invention is to remedy this difficulty; and my invention consists in constructing the line-ring in such manner as to leave the entire inclosure or inner surface of the ring perfectly smooth, as will be hereinafter fully set forth, and pointed out in the claim.

In the accompanying drawings, Figure 1 is a sectional elevation of my improved line-ring attached to a hame. Fig. 2 is a horizontal section in line x x , Fig. 1.

Like letters of reference refer to like parts in both figures.

A represents the hame, B the line-ring, and C C the staples or rivets whereby the ring is attached to the hame. The line-ring is provided at its inner side adjacent to the hame with journals d d , which are swiveled in the eyes e of the staples.

ff represent guards arranged over or in

front of the eyes of the staples C, so as to cover the same. The faces of these guards form a smooth continuation of the inner surface of the ring, as shown, whereby the formation of ridges or shoulders within the ring is avoided and the entire inner surface of the ring is left smooth, thereby preventing chafing and wear of the rein in the ring. By this construction the journals and the eyes of the attaching-staples are arranged in slotted projections wholly outside of the inner surface of the ring, as contradistinguished from an arrangement of the journals and staple-eyes directly in the peripheral line of the ring, in which latter case the staple-eyes form projections or shoulders within the ring. When the eyes of the staples project into the ring, as in rings of ordinary construction, the reins are apt to become twisted by striking the eyes and caused to bear with their narrow edges against the animal's neck, causing the hair to wear off. In my improved line-ring the reins are less liable to twist, owing to the absence of projections within the ring, and the reins are therefore more easily retained with their flat sides toward the animal.

I claim as my invention—

The combination, with a hame, of a line-ring provided on its inner side with two journals arranged one above the other in slotted projections, the slots being closed in the sides toward the interior of the ring to form internal guards covering said journals, and fastening-staples having their eyes embracing said journals and covered by said guards, substantially as set forth.

Witness my hand this 22d day of May, 1889.

JOSIAH LETCHWORTH.
